UNITED STATES PATENT OFFICE.

RAYMOND PARKS, OF CHARLESTON, WEST VIRGINIA.

CHANGEABLE EXHIBITOR.

Application filed May 16, 1922. Serial No. 561,336.

To all whom it may concern:

Be it known that I, RAYMOND PARKS, a citizen of the United States, residing at Charleston, in the county of Kanawha and State of West Virginia, have invented a new and useful Changeable Exhibitor, of which the following is a specification.

This invention has reference to changeable exhibitors, and more particularly to an exhibitor designed for displaying names of streets, or designated stops to be made by a street car or the like.

The primary object of the invention is to provide an exhibitor of this character which will insure the web, forming a part of the invention, being held in a flat unwrinkled condition when the same has been moved to display the name of a street.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

30 Referring to the drawing:

Figure 1 is a front elevational view of the exhibitor.

Figure 2 is a sectional view taken on line 2-2 of Figure 1.

35 Figure 3 is a sectional view taken on line 3-3 of Figure 1.

Referring to the drawing in detail, the reference character 5 designates the box-like body portion or container, in which the 40 spools 6 are supported, shafts 7 being shown as disposed adjacent to opposite sides of the body portion and carrying handles 8 on one of the respective ends thereof, by means of which the spools may be rotated.

45 These spools are relatively flat as clearly shown by Figure 3 of the drawing, so that when the spools are moved to bring the adjacent edges thereof into close proximity

with each other, the flat surfaces of the spools will present supporting surfaces for 50 the web moving thereover the web, which is indicated at 9, will be held in a flat unwrinkled condition while the same displays the indicating characters formed thereon.

55 As shown, the web, which may be of any suitable material, has its ends secured to the spools, whereby the same may be wound upon one spool and automatically unwound from the adjacent spool, the flat surfaces 60 providing supporting surfaces for the web 9. The cover may be of any suitable construction, the form shown in the present drawing being that of a transparent wall 10, having its side edges disposed within 65 grooves 11 formed adjacent to the upper edges of the side walls of the body portion.

In the use of the device, it is contemplated to support the body portion conveniently within the car or vehicle in which 70 the same is mounted, so that the passengers may readily view the web. It may be found desirable to place advertising matter in the respective corners of the web, so that the device will accomplish a double purpose of indicating streets or car stops as well as advertising articles.

75 Having thus described the invention, what is claimed as new is:—

In a display device, a box-like body portion, opposed spools supported to rotate within the body portion, said spools having flat surfaces, the edges of the spools adapted to move into close proximity with each other causing the flat supporting surfaces 80 of the spools to move into alignment, a web supported by the spools and said web adapted to rest on the aligning surfaces of the spools to display matter carried thereby.

85 In testimony that I claim the foregoing 90 as my own, I have hereto affixed my signature in the presence of two witnesses.

RAYMOND PARKS.

Witnesses:

CLYDE B. McLANE,
C. N. PICKENS.
